TOY RAILWAY EQUIPMENT

George W. Davis, Trenton, N. J.

Application February 25, 1937, Serial No. 127,755

2 Claims. (Cl. 191—40)

This invention appertains to new and useful improvements in electric railways and more particularly to a toy railway construction.

The principal object of the present invention is to provide a railway constructed to simulate in practically all details an electric railway of the overhead power transmission type.

Another important object of the invention is to provide a toy railway structure wherein the parts are capable of quick mounting and dismounting.

Still another object of the invention is to provide a toy railway of the overhead power transmission type wherein the transmission equipment can be used in conjunction with the conventional type of trackway now in general use.

These and various other important objects and advantages of the invention will become apparent to the reader of the following specification.

In the drawings:—

Figure 1 represents a fragmentary top plan view of the improved railway.

Figure 2 is a fragmentary side elevational view of the railway.

Figure 3 is a vertical sectional view taken substantially on the line 3—3 of Figure 2.

Figure 4 is a horizontal sectional view taken substantially on the line 4—4 of Figure 3.

Figure 5 is a sectional view taken substantially on the line 5—5 of Figure 2.

Figure 6 is a sectional view taken substantially on the line 6—6 of Figure 2.

Figure 7 is a perspective view of one of the transmission line sections.

Figure 8 is a perspective view of one of the curved sections of the transmission line.

Figure 9 is a sectional view on the line 9—9 of Figure 8.

Figure 10 is a perspective view of the overhead transmission line section located above a switchway.

Figure 11 is a sectional view on the line 11—11 of Figure 10.

Figure 12 is a fragmentary perspective view showing the base portion of one of the transmission line supporting poles.

Referring to the drawings wherein like numerals designate like parts, it can be seen in Figure 1, that numeral 5 represents straight sections of the trackway, while numerals 6—7 represent curved sections of the trackway, the section 7 being connected up with one of the sections 5 by suitable switch means 8.

At each end of each of the track sections is a metallic tie member 9 with which the usual tie

fasteners are customarily engaged for holding the track sections connected together. However, in carrying out the present invention, a base plate 10 is employed for each of the connected ends of the trackway. This base plate 10 is provided with upwardly and inwardly disposed side flanges 11 which engage the ties in the manner of the usual track connectors, but each of these plates 10 is provided with a laterally extending portion 12 to the outer end of which is secured the block 13, from which rises the post 14.

As is clearly shown in Figures 3 and 4, the upper end portion of the post 14 has a pair of arms 15—15 secured each at one end to the post 14 as at 16. A vertically disposed plate 17 is secured by suitable means 18 between the outer ends of the arms 15, while a second vertically disposed plate 19 is secured by means 20 between the inner end portions of the arms 15. An eye member 21 on the upper end of the post 14 has the hook end 22 of the brace rod 23 engaged therewith while the lower end of this brace rod 23 is provided with the hook 24 engaged through an opening in the upper portion of the plate 17. Wooden insulators 25—26 are provided for each post 14 and each is provided with an eye 26 at its upper end disposed through an opening in the corresponding plates 17 or 19. An eye 27 is provided at the lower end of each of these insulators, which of course may be of some other material besides wood and from these eyes 27 depend the coiled extensible springs 28—29. The spring 29 is attached to the lower end or eye 30 of the spring 28.

As shown in Figure 7, the straight transmission line section is generally referred to by numeral 31 and consists of the straight tubular conductor 32 connected by the members 33 to the longitudinally curved brace rods 34. One end of the transmission member 22 has a pin 35 forced into the same and at this point is located the hook 36 which is engageable with the corresponding overlying spring eye 30. (See Figure 3.) Each end of each of the brace members 34 is provided with an eye 37 and these eyes 37 overlap in the manner shown in Figure 6 with the eye 27 of the insulator 25 disposed through the same. Thus the transmission line section is supported in place. The curved section of the transmission line is generally referred to by numeral 38 which is provided with the tubular curved conductor 32a provided with the connecting pin 35a at one end and the supporting hook 36a and also the brace rod 34a connected as at 33a to the con-

ductor 32a, the brace rod 34a being provided with the eyes 37a at its ends.

The type of transmission line section employed over the switch area 8 of the trackway (see Figure 1) consists of the elongated straight conductor 32b and the elongated curved brace rod 34b provided with the usual eyes 37b at its ends, this brace rod 34b being connected by the members 33b to the conductor 32b.

10 Curving laterally away from the intermediate portion of the conductor 32b is the branch conductor section 39 above which is the curved brace member 40 connected by members 41 to the conductor 39 and equipped with the end eye 42.

15 Suitable brace means 43 is provided between the conductors 32b and 39 as well as between the braces 40 and 34b and the said conductors 32b and 39.

20 The conductors 32, 32a, 32b and 39 will be disposed as much as possible directly over a center of the trackway.

Furthermore, the eyes at the ends of the brace rods 34, 34a, 34b and 40 will have shanks which are driven into the tubular brace member 34.

25 While the foregoing specification sets forth the invention in specific terms, it is to be understood that numerous changes in the shape, size and materials may be resorted to without departing from the spirit and scope of the invention as 30 claimed hereinafter.

Having described the invention what is claimed as new is:—

1. In a toy electric railway system including a track and sleepers supporting the track, an overhead third rail structure including poles detachably secured to said sleepers, an arm extending laterally from each pole over said track, an insulator suspended from the outer end of each arm, a transmission line including grid-like sections

of tubular metal detachably secured together in end-to-end adjoining relation and each comprising a lower rod for engagement by a trolley and an upper brace rod, and means for detachably securing said sections to said insulators comprising eyelet members on the ends of the upper rods, eyebolts in the bottom of the insulators extending through the eyelet members of adjoining upper rods, respectively, coiled springs depending from the eyebolts and terminating in loops, and hooks on the ends of the lower rods extending through said loops.

2. In a toy electric railway system including a track and sleepers supporting the track, an overhead third rail structure including poles detachably secured to said sleepers, an arm extending laterally from each pole over said track, an insulator suspended from the outer end of each arm, a transmission line including grid-like sections of tubular metal detachably secured together in end-to-end adjoining relation and each comprising a lower rod for engagement by a trolley and an upper brace rod, and means for detachably securing said sections to said insulators comprising eyelet members on the ends of the upper rods, eyebolts in the bottom of the insulators extending through the eyelet members of adjoining upper rods, respectively, coiled springs depending from the eyebolts and terminating in loops, and hooks on the ends of the lower rods extending through said loops, and means to yieldingly brace said line against side sway comprising insulators secured to the arms adjacent the rear ends of the latter, and coiled springs connected at their opposite ends to said last mentioned insulators and to the loops of the first mentioned springs respectively.

GEORGE W. DAVIS.
